(57) **CLAIM**

The ornamental design for an insect trap, as shown and described.

DESCRIPTION

FIG. 1 is a perspective view of an insect trap showing a new design.

FIG. 2 is a perspective view of the insect trap showing a new design from the rear.

FIG. 3 is a front view thereof.

FIG. 4 is a rear side view thereof.

FIG. 5 is a left side view thereof.

FIG. 6 is a right side view thereof.

FIG. 7 is a top plan view thereof; and,

FIG. 8 is a bottom plan view thereof.

The broken lines depict portions of the insect trap that form no part of the claimed design.
